US00D530562S

(12) **United States Design Patent** (10) **Patent No.:** **US D530,562 S**
Brookshire et al. (45) **Date of Patent:** **** Oct. 24, 2006**

(54) **STAND-ALONE SELF-SUPPORTING
DISPOSABLE HEART SHAPED BAKING CUP**

(75) Inventors: **Phillip L. Brookshire**, Cincinnati, OH (US); **Jennifer Danich O'Flynn**, Richmond, VA (US); **Monica Stautner Nichols**, Richmond, VA (US)

(73) Assignee: **Alcoa Inc.**, Pittsburgh, PA (US)

(**) Term: **14 Years**

(21) Appl. No.: **29/243,574**

(22) Filed: **Dec. 21, 2005**

(51) **LOC (8) Cl.** **07-02**

(52) **U.S. Cl.** **D7/354**

(58) **Field of Classification Search** ..... D7/323, D7/354, 356, 357, 359, 360, 409, 500, 552, D7/554.1, 554.2, 554.3, 554.4, 556; D9/456; D15/90; 99/422, 425, 426, 428, 430, 432, 99/439-442, 444, 446, DIG. 15; 206/557, 206/561-564; 220/405, 445, 447, 469, 500, 220/507, 508, 553, 555, 575, 626
